UNITED STATES PATENT OFFICE.

WILLIAM D. GOLD, OF CARTHAGE, TENNESSEE.

STOVE.

SPECIFICATION forming part of Letters Patent No. 746,817, dated December 15, 1903.

Application filed August 14, 1903. Serial No. 169,526. (No model.)

To all whom it may concern:

Be it known that I, WILLIAM D. GOLD, a citizen of the United States, residing at Carthage, in the county of Smith and State of Tennessee, have invented certain new and useful Improvements in Stoves; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in stoves; and it consists in the provision of means whereby different kinds of fuel may be successfully burned by the provision of the peculiar arrangement of grates and in the provision of means whereby the smoke may be consumed and affording means whereby rooms in which the stove is positioned may be thoroughly ventilated.

The invention consists, further, in various details of construction and in combinations and arrangements of parts, which will be hereinafter fully described and then specifically defined in the appended claims.

My invention is clearly illustrated in the accompanying drawings, which, with the letters of reference marked thereon, form a part of this application, and in which drawings—

Figure 1 is a sectional perspective view of my improved stove. Fig. 2 is a rear elevation of the stove complete, showing the vent or air-inlet flues. Fig. 3 is a detail view of the under or stationary grate. Fig. 4 is a detail view of a cylindrical ventilator adapted to rest upon the grate when burning a certain kind of fine fuel. Fig. 5 is a detail view of a similar cylinder which is adapted to rest upon the cylinder shown in Fig. 4 to form a pyramidal ventilator for burning slack, and Figs. 6 to 16, inclusive, are detail views.

Reference now being had to the details of the drawings by letter, A designates the base portion of the stove, supported by legs A', and B designates an ash-box underneath said base portion provided with a suitable door, and mounted upon the platform of the base A, which is provided with an annular rib or flange a, is a shell C, having a flange C' at

its lower end fitting to the flange a and has a cut-away portion C². The upper edge of the cylindrical portion of the shell C has scallops or recesses C³ at intervals, and resting upon the upper end of said shell is a ring D, which is of a larger diameter than the body portion of the shell C and has series of apertures D' in the portion which overhangs the shell C. Said ring D has an annular flange d, and resting upon the portion of said ring inside of the flange d is a grate E, a detail view of which is shown in one of the figures of the drawings, said grate having a series of radial openings E' and at the center intersecting cross-bars F, which span a circular-outlined opening F', and at the point of intersection of said bars is an aperture f, while shoulders f' are provided near the ends of said bars. Surrounding a flange G about the circular-outlined aperture F is a movable grate H, having series of radial apertures H' therein which are adapted as the movable grate is rotated to close or partially close the apertures in the grate E, or, if desired, the apertures in the two grates may be brought into registration with one another. Said movable grate is provided with an arm h, having a crank h', which passes underneath the circular ring D and projects through the opening intermediate the ends of the shell C in a convenient position to receive a shaking-handle H².

Resting upon the ring D is a fire-pot made up, preferably, of four sections and designated in the drawings by letter K. Said fire-pot has a series of integral flanges K', K², and K³ thereon, the former of which, K', is positioned a short distance above the flange of the ring D, forming with the surrounding wall of the stove a hot-air compartment. The second flange K² is provided with a series of circumferential cut-away portions k, while the circumference of the fire-pot intermediate the flanges K² and K³ has apertures I formed therein, through which the heated air passing through the recesses about the circumference of the flanges k may pass through into the interior of the stove for the purpose of providing heated air to assist in furthering the combustion of gases within the fire-pot. The third flange about the fire-pot supports the cone N, made up of two

sections which are securely fastened together, the upper portion of the cone being of cylindrical shape, as at N', to receive a pipe for conveying smoke from the fire-pot. Upon 5 the inner circumference of the fire-pot adjacent to its lower end is a flange O, which is adapted to support fire-brick P, which have apertures P' therein adapted to register with the apertures I, formed in the circumference 10 of the fire-pot.

Resting upon the flange K² is a band Q, having a series of scallops or outwardly-flaring portions Q' designed to be positioned adjacent to each of the apertures in the wall of 15 the fire-pot and provided for the purpose of allowing air to readily enter said apertures, but to prevent soot or ashes from coming out of the fire-pot. Said corrugations or outwardly-flaring portions are so constructed 20 that should any ashes happen to come out of the holes they will be directed back by gravity through the holes whence they came. The outer wall of the stove is designated in the drawings by letter R, and fastened to the 25 latter a little above the shoulders n of said cone is a circular disk J, with its bottom largely cut away and is provided with a flange J' and is adapted to coöperate with the outer shell R to hold the air in contact with 30 said cone. Resting upon the upper end of the outer wall R a few inches above the disk J is a flanged top L, having spokes L', which connect said top with a central ring L², which is of a size adapted to let the smoke-pipe pass 35 through it after the latter is made to fit over the cylindrical end N' of the cone. A conveyance-drum S is adapted to fit over a flange L³ of said top, and apertures open near the top of the drum for connection to pipes 40 through which heat may be conveyed to registers located in various rooms, while the smoke-pipe fits over the end of the cylindrical part of the cone and extends centrally 45 through the heating-drum.

When it is desired to adapt the stove to use various kinds of fuels, the plates T and T' may be placed over the central opening in the grate, or if desired to build up a pyramidal ventilator the cylindrical shell W, 50 having vertical slots in its cylindrical portion and an open center, may be placed about the flange of the grate E, and still another cylindrical shell V, having vertical slots, may be inserted in the central aperture in the cylindrical shell W and supported thereby, and if desired to use one of said cylindrical shells 55 and to close the central opening therein a plate X may be placed over said central aperture. If desired to use still another attachment in place of the cover X, a grate U, having radiating bars, may be positioned inside of the shell W, with the shank portion U' of 60 said grate U resting in the central aperture of the grate E.

In order to allow air to enter the compartment intermediate the ring D and the flange K', I provide ducts D⁴, which are shown in 65

the rear portion of the body of the stove, while similar ducts D⁵ lead to the space intermediate the flanges K' and K². 70

Referring to Fig. 14 of the drawings, I have shown a thimble N² of truncated conical shape which is adapted to fit over and rest upon the flanges of the fire-pot N, and said thimble is provided with a series of radial longitudinally-disposed flanges N³, intermediate which are elongated slots N⁴, through which the heated air radiating from the conical-shaped member N is allowed to pass into the hot-air chamber before entering the conveying-chamber S. Said thimble extends nearly the length 75 of the cone N and serves the purpose of preventing the stove from making a small room too hot, because the thimble will interpose a wall between the cone and the drum and in some degree arrest the heat, while, in the second place, it will serve as a heating-board, as it will become very hot and radiate its heat into both the column of air that is passing up between the thimble and the cone and also 80 that passing between the thimble and the outer wall of the stove, thus serving for heat what a sounding-board would for sound. If desired, this thimble may be removed and the stove utilized without it by simply lifting the 85 cone off the hole upon which it rests.

As a means for getting the air between the walls of the stove to be heated for use in warming the rooms I have provided a large circular opening in the rear of R near the bottom 90 of the cone, into which a pipe reaching the outdoor space is to be inserted for conveying fresh air into the space between the walls of the stove, there to be heated for warming and 95 ventilating purposes, also other openings in R at base of cone to admit air for same purpose from the room in which the stove is situated, and in the event no fresh-air pipe is necessary or practicable for the circular opening it is to have a grate placed upon it and 100 is also to admit air, as the others, from the same room. 105

When the fresh-air pipe is inserted in the circular opening, a damper is to be placed in the pipe to control the influx of cold air from 110 outdoors, as the state of the weather or other circumstances may demand. The air admitted between the walls by either or all of these openings is heated all the way up the sides 115 of the cone and passing into the large conveying-pipe S continues to be heated by the smoke-pipe all the way up to its top or to the branch pipes, wherever they may be inserted, 120 when any are used. I have also provided a shield Q⁵, attached to the inner side of the 125 upper front door, and when so attached it constitutes a box open only at the upper end. Through the center of the door is a duct similar to D⁴ for air to enter into the shield-box, 130 where it becomes hot and passes up out of the box and inward and upward through the apex of the cone, giving further supply of hot air for smoke and gas consuming purposes.

In operation air is allowed to enter the vent-

flues into the chamber between the ring D and the flange K', and coming in contact with the outer circumference of the fire-pot it becomes somewhat heated before passing through the apertures D'. After passing through said apertures the air will enter the recesses at the upper end of the shell C underneath the grate. The second current of air utilized for consuming the smoke and gases will enter through the vent-ducts D⁵, which communicate with the compartment above the flange K' and enter the apertures P' into the interior of the fire-box, where the air which has been heated by its circulation comes in contact with the heated gases in the fire-box and assists in the further combustion of the soot and smoke in the stove.

By the provision of the various adjusting features it will be readily seen that my stove may be adapted for use in burning either coke, wood, anthracite or lump coal, and slack, and by the provision of the double hot blast the soot and smoke will be thoroughly consumed, thereby securing the maximum heat from the fuel. As the products of combustion are so thoroughly consumed, very little smoke, gases, and soot are encountered.

While I have shown a particular form of apparatus embodying the features of my invention, it will be understood that I may make alterations in the detailed construction of the same, if desired, without departing from the spirit of the invention.

Having thus fully described my invention, what I claim as new, and desire to secure by Letters Patent, is—

1. A stove comprising a base portion, an ash-box thereunder, a shell supported upon said base, a fire-pot and grates supported upon said shell, hot-air-chambers surrounding the fire-pot and air-feeding pipes leading to said chambers and communicating with the interior of the fire-pot, a cone positioned over the fire-pot and surrounded by said shell, as set forth.

2. A stove comprising a base portion mounted upon suitable legs, a shell supported upon said base having a series of recesses formed in its upper edge, a flanged ring seated upon said shell having a series of apertures outside of the circumference of said shell, grates supported by said shell, a fire-pot resting on said ring, a cone mounted upon the fire-pot, a flange adjacent to the lower end of the fire-pot forming with said ring a compartment in which air enters for the purpose of supplying oxygen for combustion purposes, and a ventilating-duct leading into said compartment, as set forth.

3. A stove comprising a base, a flanged shell mounted thereon having scallops about the upper edge of its cylindrical portion, a ring seated upon said shell having apertures in its overhanging portion, grates supported by said ring, a fire-pot resting upon said ring and having annular flanges about its circumference, an air-feeding duct leading to a com-

partment intermediate said ring and the lower flange of the fire-pot, the edge of one of said flanges being recessed, and the wall of the fire-pot apertured, and an air-feeding duct communicating with the interior of the fire-pot through said recesses and apertures, a surrounding shell to the stove, and a cone supported on the fire-pot, as set forth.

4. A stove comprising a base portion with ash-box thereunder, a flanged shell mounted upon said base and having scallops about the upper edge of its cylindrical portion, a flanged ring seated upon said shell having apertures in its overhanging portion, a stationary grate supported by said ring, a movable grate resting upon the stationary grate and having an arm with a crank-pin extending underneath said ring, a fire-pot resting upon said ring and having annular flanges about its circumferences, the central of said flanges having recesses about its edge, and apertures through the wall of the fire-pot, a surrounding shell to the stove, a cone resting upon the fire-pot, and air-feeding ducts leading to the spaces intermediate said flanges, as set forth.

5. A stove comprising a base, a flanged shell mounted upon said base and having series of recesses about the upper end of its cylindrical portion, a flanged ring seated upon said shell having apertures in its overhanging portion, a fixed grate resting upon said ring, a movable grate mounted upon the fixed grate and having an arm with pin extending underneath said ring, a fire-pot resting upon said ring having annular flanges, the intermediate one of said flanges being scalloped, a shell surrounding said fire-pot, a cone resting upon the latter, air-feeding ducts leading to the spaces intermediate said flanges, the inner wall of the fire-pot having an annular flange, and fire-brick resting upon said flange and having apertures in registration with holes in the circumference of the fire-pot, as set forth.

6. A stove comprising a base portion, a flanged shell resting thereon, the upper edge of the cylindrical portion of said shell being recessed out, a flanged ring seated on said shell, a stationary grate mounted upon said ring, and a movable grate mounted upon the fixed grate, a pyramidal ventilator supported by said stationary grate, a fire-pot supported by said ring and having annular flanges about its circumference, one of which has circumferential recesses, a shell surrounding the fire-pot, a cone mounted upon the latter, and air-feeding ducts leading to and communicating with the spaces intermediate said flanges, as set forth.

7. A stove comprising a base portion, a flanged shell mounted thereon, the cylindrical portion of said shell having recesses about its upper edge, a flanged ring seated upon said shell having apertures in its overhanging portion, a stationary grate supported by said ring, a movable grate mounted upon the fixed grate having a crank-pin pro-

jecting underneath said ring, a fire-pot resting upon said ring and having series of annular flanges, one of which has recesses about its circumference, a shell surrounding said 5 fire-pot, a sectional cone mounted upon the fire-pot, and air-feeding ducts leading to the spaces intermediate said flanges, as set forth.

8. A stove comprising a base portion, a flanged shell mounted thereon, the upper edge 10 of the cylindrical portion of said shell having recesses, a flanged ring seated on said shell having apertures in its overhanging portion, grates supported by said ring, a fire-pot, the wall of which is apertured and provided with 15 annular flanges, spaced apart, one of said flanges having recesses about its circumference, a circular plate resting upon one of said flanges and having flaring guard portions adjacent to the apertures in the wall of the fire- 20 pot, a shell surrounding the fire-pot, a cone resting upon the latter, and air-feeding ducts leading to the spaces intermediate said flanges, as set forth.

9. A stove comprising a base portion, a flanged shell mounted thereon, the upper edge 25 of which is recessed, a flanged ring seated upon said shell, and having apertures in its overhanging portion, grates supported by said ring, a fire-pot with apertured circumference and annular flanges, one of which is recessed about its circumference, a shell surrounding said fire-pot, a cone resting upon the latter, air-feeding pipes leading to the 30 spaces intermediate said flanges, a horizontally-disposed disk suspended near the top of a flanged top supported by the shell above said disk, and a conveyance-pipe resting upon said top, as set forth.

10. A stove comprising a base portion, a flanged shell mounted thereon, the upper edge 35 of which is recessed, a ring seated upon said shell and having apertures in its overhanging portion, a grate having radial apertures therein, and having central bars spanning an annular recess inside of said apertures, a movable grate mounted about a flanged part of said ring, a fire-pot having annular flanges and apertured wall, one of said flanges having recesses about its circumference, ducts 40 leading to the spaces intermediate said flanges, a shell supported upon said grate

having vertical slots in its cylindrical portion, and a grate member having a shank portion supported in a central aperture in said fixed grate, a shell surrounding the fire-pot, and 55 air-feeding ducts leading to the spaces intermediate the flanges; a cone supported by the fire-pot, a disk supported near the top of a smoke-pipe leading from the cone, and a surrounding hot-air-conveyance pipe, as set forth.

11. A stove comprising a base portion, a flanged shell mounted thereon, the upper edge 60 of which is recessed, a ring seated upon said shell and having apertures in its overhanging portion, a grate having radial apertures therein, a movable grate, a fire-pot, a shell surrounding the fire-pot, a cone resting upon the latter, an open-ended thimble resting upon said cone and spaced apart therefrom, 65 flanges upon the outer circumference of said cone, and slots in the thimble intermediate said flanges, as set forth.

12. A stove comprising a base portion, a flanged shell mounted thereon, a fire-pot and 70 grate supported upon said shell, a hot-air chamber surrounding said pot, air-feeding passage-ways leading to said chamber and communicating with the interior of the fire-pot, a cone positioned over the fire-pot, a surrounding shell with ventilating-openings adjacent to the lower end of the cone, a smoke-pipe connecting to the top of the cone, and a heat-conveying pipe supported above the shell and communicating with the chamber 75 beneath, as set forth.

13. A stove comprising a base portion, a shell supported thereon, a fire-pot and grate supported upon said shell, a hot-air chamber surrounding the fire-pot, air-feeding passage- 80 ways communicating with the interior of the fire-pot, a cone positioned over the fire-pot, a door leading into the fire-pot provided with an air-feeding aperture, a shield with open top carried by said door, a shell surrounding 85 the fire-pot and cone, as set forth.

In testimony whereof I hereunto affix my signature in presence of two witnesses.

WILLIAM D. GOLD.
